UNITED STATES PATENT OFFICE.

MYRON W. ELLIOTT, OF ELGIN, ILLINOIS, ASSIGNOR TO THE ELLIOTT & MOSELEY WATCH SPRING COMPANY, OF SAME PLACE.

DIE FOR DRAWING WATCH-SPRINGS.

SPECIFICATION forming part of Letters Patent No. 333,735, dated January 5, 1886.

Application filed September 18, 1885. Serial No. 177,439. (No model.)

To all whom it may concern:

Be it known that I, MYRON W. ELLIOTT, of Elgin, in the county of Kane and State of Illinois, have invented a new, useful, and Improved Device for Finishing Watch-Springs, of which the following is a description, reference being had to the accompanying drawings, in which—

Figure 1 is a rear view of said device. Fig. 2 is a front view of the same. Fig. 3 is a central vertical sectional view thereof, with reels for holding and drawing the ribbon of metal. Fig. 4 is a horizontal sectional plan view in detail, taken upon the line $x x$, Fig. 1. Fig. 5 is a side view of a middle portion of the frame, showing a removable cap for use in the adjustment of a horizontal slide. Fig. 6 is a detail view of portions of the movable vertical and horizontal slides detached from their bearings; and Fig. 7 shows a face and side view, respectively, of the dies attached to said horizontal slides.

Like letters of reference designate corresponding parts in the various figures.

The purpose of my invention is to provide a device or mechanism whereby ribbons of metal, and especially the mainsprings of watches, may be rendered smooth and uniform in width and thickness upon being passed through the same, while at the same time a greater tensile strength, as well as a perfect finish, may be imparted thereto. Said device consists of a series of adjustable dies formed, preferably, from diamonds or other gems of similar hardness and capable of receiving a high polish, said dies being constructed, arranged, and adjusted substantially in the manner hereinafter more particularly described, and definitely pointed out in the claims.

In the drawings, A represents the frame of said device, which consists, preferably, of a single block of steel, having vertical and horizontal grooves planed therein for the reception of the die-holding slides, as hereinafter described. A central vertical slot (indicated by the outermost dotted lines in Figs. 1 and 2) is extended from the top to the middle of said frame, into which is inserted an adjustable guide-block or sub-frame, B, (also indicated in dotted lines in said figures, and shown in Figs.

3 and 4,) said block being provided with a trunnion or arbor, b, Figs. 2, 3, and 4, accurately fitted within a circular bearing in the block A. The groove into which said block B is placed is somewhat wider than said block, 55 as shown by said dotted lines, so that, were it not for the trunnion b, the entire block might have a slight lateral movement; but as constructed it is obvious that the lower end only can be so moved, the same describing a slight 60 arc, of which b is the center. By inserting screws horizontally into the block A, as indicated in dotted lines at $a a$, Figs. 1 and 2, and also shown in Fig. 5, the lower end of said block B may be adjusted laterally with the 65 nicest accuracy. Said block B is provided with a suitable slot or groove, into which is accurately fitted a slide, C, Figs. 3, 4, and 6, and likewise shown in dotted lines in Figs. 1 and 2. In a like vertical groove, extending from the middle to the lower end of the block A, I place a similar slide, C', which should be carefully fitted, so as to admit of no lateral play. Plates D D are attached to the respective ends of the block A by means 75 of screws $d d$, Figs. 1 and 2, which said plates are preferably provided with reinforcing bosses or shoulders $d' d'$, forming a part thereof, through which are inserted adjusting or set screws $d^2 d^3$, the former of which is provided with an enlarged head or thumb-piece, upon the periphery of which is a graduated scale, d^4 , Fig. 2, which is designed to be operated in conjunction with a stationary post or indicator, d^5 , rigidly attached to the plate 80 D. The inner ends of the screws $d^2 d^3$ abut against the ends of the slides C C', respectively, and the pitch of said screws should be very fine, in order to permit of the most delicate 85 adjustment of the slides, it being practicable 90 to so proportion said scale d^4 in conjunction with the pitch of said screw d^2 as to indicate a movement of the slide E of one-one-hundred thousandth of an inch. Said slides are retained in place in their respective grooves by 95 means of a face-plate, a' , Figs. 1, 3, and 4, attached to the block A by means of screws a^2 , Fig. 1, said face-plate being provided with an opening, a^3 , Fig. 1, in the middle and opposite the meeting ends of the slides C C'. Into said 100

meeting ends of the slides C C' are rigidly secured dies E E', Figs. 1, 2, and 3, and indicated in dotted lines in Figs. 5 and 6. Said dies or slide-facings are preferably constructed 5 of diamond, sapphire, ruby, chrysolite, iridium, black carbon, topaz, corundum, crystallized hematite, adamantine spar, or other like stone or material possessing great hardness, and their respective faces should be 10 highly polished and rounded transversely, as shown in Fig. 3, while they are straight in the opposite direction, in which it is of the utmost importance that they should be parallel with each other. Should any slight inaccuracy 15 in this respect occur in forming them, I am enabled to overcome it by means of the adjustable block B, which, upon turning the screws a a, may be moved laterally in one or the other direction until perfect accuracy is 20 obtained and said jeweled facings are rendered exactly parallel with each other.

Across and into the front of the block or frame A, I cut a dovetail groove, the center of which is in a plane with the point of juncture 25 of the dies E E' and opposite the opening a' in the plate a', into which groove I insert a single slide, F, Figs. 2 and 3, which is in turn provided with a corresponding groove, into which are accurately fitted horizontal slides G 30 G. Said slide or grooved plate F is perforated opposite the meeting ends of the slides G G', which is likewise opposite said opening a', said plate thereby serving to give greater accuracy to the movement and to form a firmer 35 support for the slides G G', the meeting ends of which might otherwise rest partly against the back of the block B. Detachable plates f f', Figs. 2 and 5, are also secured to the respective ends of the plate F by means of screws f', 40 Fig. 5, while the whole is retained within the frame A, and its longitudinal movement adjusted by means of adjusting screws f' f', one of which is shown in said last-named figure. By this arrangement the slides G G' when ad- 45 justed to the width of a spring, as hereinafter stated, may both be given a longitudinal movement in one or another direction without varying said adjustment, by which means the spring or metal ribbon may be adjusted lat- 50 erally, if desired, in its relation to the dies E E'. To the meeting ends of the slides G G', I rigidly attach diamond or other similar dies or facings, H H, each of which is provided 55 with a semicircular or curved notch, h, (better shown in Fig. 7.) which is an enlarged view of the face of one and the side of the other of said dies. The notch h is preferably countersunk upon the outside, as at h', Figs. 1 and 7, and is gradually enlarged from the middle out- 60 wardly in both directions, substantially as indicated in the face view of said Fig. 7, the size of said notches corresponding approximately with the thickness of the mainspring to be treated, their purpose being to round the edges 65 of said spring.

In using said device the frame A is clamped

or otherwise secured in an upright position within a secondary frame or holder, J, Fig. 3. The end of the steel ribbon or spring K, Fig. 3, which is wound upon a suitable reel, L, is 70 passed between the dies H H and E E', respectively, and attached to the drum of a similar reel, L'. Said dies H H are then adjusted by means of the set-screws f' f', and E E' by the screws d' d', to press upon said spring K. Upon 75 turning the reel L' by means of the handle l, or in any other way, the spring K is drawn between said dies, which should be kept continually oiled. If, upon testing the portion of the spring thus submitted to the dies, one edge 80 is found to be thinner than the other, the defect may be remedied by a lateral adjustment of the block B, as described. I preferably draw the spring K through said dies several times, to insure perfect uniformity and finish, 85 each repetition of the operation being accompanied by a slight closing of the dies, the adjustment, particularly of the dies E E', being made with great care by means of the scale d', which should provide for the utmost practical 90 delicacy of action. It is obvious that as said dies are made in parts and detachable the respective faces thereof may be readily smoothed and polished in the event of the slightest abrasion, which would not be true of 95 a round or oblong hole cut through a solid piece of material. This fact obviates the necessity for replacing said dies when so injured, while the cost of repairing the same is but nominal. Moreover, the lateral and longitudinal adjustment of said dies in the manner described enables me to produce springs of an indefinite length, of any size desired, and of uniform thickness and width.

Upon applying a gage capable of registering 105 one five-thousandth of an inch I have been unable to detect the slightest variation, either in width or thickness, in a ribbon of steel fifty feet in length and finished in the manner described, while a spring a few inches in length, 110 made under the old method, by means of rubbing upon a flat surface with abrading material, will show the most marked inaccuracies in both of said respects. It is wholly impracticable to produce a spring of uniform width 115 and thickness by means of appliances and methods heretofore in use. The faces or sides of the best springs in the market are more or less rounded, leaving said springs thicker in the middle, while the variations in thickness 120 and width cause them to break more readily than they otherwise would. Said dies not only produce perfect uniformity in said metal strip, as stated, but impart a fine polish and finish thereto and increase the toughness and tenacity 125 of its fiber. I am enabled, therefore, by means of said device or apparatus to produce a watch-spring of a character, quality, and accuracy of form heretofore unknown.

It is obvious that the slides G G' and C C' 130 may be placed in separate frames apart from each other, and the strip of metal passed

through the same, respectively, by separate operations without varying the essential features of my invention; but such change would increase the cost of the product, while the results would be more or less inferior. It is, moreover, apparent that said dies may be made wholly of precious stones or other material of the description named; but this would render the same unnecessarily expensive, as it is immaterial what the slides themselves are composed of, so long as they are strong and durable and are faced upon the meeting ends substantially as specified.

Having thus described my invention, what I claim, and desire to secure by Letters Patent, is—

1. In a device for finishing watch-mainsprings or other analogous ribbons of metal, a pair of slides or dies faced with precious stones, jewels, or other equivalent stones, hard substances, or material capable of receiving a uniform polish and surface, and arranged to compress the sides of said springs, substantially as and for the purposes specified.
2. In a device or apparatus for finishing watch-mainsprings or other analogous ribbons of metal, a pair of slides or dies faced with precious gems, jewels, or other equivalent stones, hard substances, or material capable of receiving a uniform polish and surface, and arranged to compress the edges of said springs, substantially as and for the purposes specified.
3. In a device for finishing watch-mainsprings or other analogous ribbons of metal, a pair of adjustable slides or dies faced with precious gems, jewels, or other equivalent stones, hard substances, or material capable of receiving a uniform polish and surface, and arranged to compress the sides or faces of said springs, substantially as and for the purposes specified.
4. In a device or apparatus for finishing watch-mainsprings or other analogous ribbons of metal, a pair of adjustable slides or dies faced with precious gems, jewels, or other equivalent stones, hard substances, or material capable of receiving a uniform polish and surface, and arranged to compress the edges of said springs, substantially as and for the purposes specified.
5. In an apparatus for finishing watch-mainsprings or other analogous ribbons of metal, a series of adjustable slides or dies faced with precious gems, jewels, or equivalent stones, hard substances, or material capable of receiving a uniform polish and surface, and arranged to compress the sides or faces and edges of said springs at one operation, substantially as described.
6. An apparatus for imparting uniformity of width and thickness to watch-mainsprings or analogous metal strips, consisting of a series of adjustable slides or dies faced with precious stones, jewels, or other equivalent stones, substances, or material capable of receiving a uniform polish and surface, arranged to compress

the sides and edges of said spring, and means for drawing said spring between the same, substantially as described.

7. A device or apparatus for finishing watch-mainsprings or analogous metal strips, provided with a series of adjustable jewel-faced slides arranged in a suitable frame to compress said springs from opposite directions, whereby uniformity in width and thickness may be imparted to the latter, substantially in the manner described. 75

8. A device for finishing mainsprings provided with a pair of adjustable jewel-faced slides or dies arranged in a given plane, and a similar pair of jewel-faced slides or dies arranged in a plane perpendicular thereto, the faces of one pair of said dies having paraboloidal or curved notches therein and those of the other being straight, whereby the edges of the spring may be rounded simultaneously 85 with the parallel flattening of its sides, substantially as described.

9. In a finishing device for watch-mainsprings or analogous metal strips, the combination of a pair of longitudinally-adjustable jewel-faced slides and a laterally-adjustable sub-frame for one of said slides, whereby the faces may be made parallel with each other in use, substantially as and for the purposes 95 specified. 90

10. In a finishing device for watch-mainsprings or like metal strips, the combination of a pair of longitudinally-adjustable jewel-faced slides, movable in opposite directions in the same plane, and a trunnioned sub-frame for the reception of one of said slides, with means, as set-screws, for the lateral adjustment of its jeweled end in the arc of a circle, substantially as and for the purposes specified. 100 105

11. In a device for rendering metal strips parallel and uniform in width and thickness, the combination, with a suitable frame, of the jewel-faced slides G G and C C', having screws, respectively, for adjusting the same longitudinally, substantially as described. 110

12. In a device for rendering metal strips uniform in width and thickness, the combination of the jeweled-faced slides G G and C C', means, as screws, for adjusting the same longitudinally, and the trunnioned block B, with suitable screws for adjusting the same laterally, substantially as and for the purposes set forth. 115

13. The combination, with a suitable frame, of the longitudinally-adjustable slide F, having the jewel-faced slides G G, arranged in a groove therein, and jewel-faced slides C C', each of said slides, respectively, having one or more set-screws, whereby the same may be adjusted in the direction of its length, substantially as described. 120 125

14. In a device for rendering metal strips uniform in width and thickness, the combination of the slides G G and C C', having their meeting ends provided with dies formed from diamonds or other hard stones or materials, and adjusting-screws for moving said dies long- 130

5 longitudinally, one of said screws controlling the dies, which compress the flat sides of the metal strip, having an enlarged head with a graduated scale upon its periphery, whereby the extent of its rotation, with reference to a stationary indicator, may be shown, substantially as set forth.

15. In a device for rendering metal strips

uniform in width and thickness, the adjustable jewel-faced slides G G C C', and a suitable reel 10 or reels for drawing the metal strips between the same, substantially as described.

MYRON W. ELLIOTT.
